UNITED STATES PATENT OFFICE.

WILLIAM KELLEY, OF FALL RIVER, MASSACHUSETTS.

DEVICE FOR REMOVING PRESSURE FROM ROLLS OF SPINNING-FRAMES, &c.

SPECIFICATION forming part of Letters Patent No. 309,062, dated December 9, 1884.

Application filed November 14, 1883. (No model.)

To all whom it may concern:

Be it known that I, WILLIAM KELLEY, of Fall River, in the county of Bristol and State of Massachusetts, have invented certain Improvements in Devices for Removing Pressure from Rolls of Spinning-Frames, &c., of which the following is a specification.

This invention consists in devices for relieving the pressure of the upper rollers of spinning-frames or other analogous machines upon the lower rollers thereof when the machine is not in use, thereby preventing the leather surfaces of the upper rollers from being indented or grooved by continued pressure against the fluted metal surfaces of the lower rollers while said rollers are motionless.

It is well known that the leather-covered upper rollers of a spinning-frame are pressed against the fluted lower rollers by an imposed weight which gives a downward pressure of about sixty pounds, so that when the machine is at rest, as at night, this pressure, if continued, causes the fluted rollers to make grooves or serrations in the leather surfaces of the upper rollers. Said grooves or serrations, when the operation of the machine is resumed, in connection with the serrations or flutings of the lower rollers, cut and injure the roping or sliver, and the leather covers have to be more or less frequently removed and renewed on this account.

Of the accompanying drawings, forming a part of this specification, Figure 1 represents a front view, partly in elevation and partly in section, of a portion of a spinning-frame provided with my improvements. Fig. 2 represents a section thereof on line $x x$, Fig. 1.

The same letters of reference indicate the same parts in all the figures.

In the drawings, $a a a$ represent the upper rollers, and $b b b$ the lower rollers, of a spinning-frame, the upper rollers being covered with leather, and the lower ones being fluted longitudinally, as usual. The lower rollers are driven by power, and are journaled in metal bearings in the usual manner. The upper rollers rest on the lower ones or upon the interposed ropings, and are pressed downwardly by weights c , applied to levers d , which are pivoted at e to the roll-beam of the machine, or to the lower portion of the creel, and are connected by stirrups f with saddles g , resting on the reduced ends or journals of the rollers a , the weights c being thus imposed on the rollers a .

The construction thus far described is old and well known, and forms no part of my invention.

In carrying out my invention I provide a rock-shaft, i , journaled in brackets or supports $j j$, attached to the frame of the machine, and extending substantially parallel with the axial lines of the rollers $a b$. Said rock-shaft has a series of eccentrics, k , affixed to it at points under the levers d , on which the weights c are placed. Said eccentrics are arranged so that, when the rock-shaft is turned to elevate the eccentrics, as shown in dotted lines in Fig. 2, they will bear against and raise the levers d , and thus entirely relieve the rollers a of the imposed pressure caused by the weights c . When the rock-shaft is turned so as to depress the eccentrics, as shown in full lines in Fig. 2, the eccentrics do not support the levers d , but allow the weights to act on the rollers a . The rock-shaft is provided with a suitable operating-lever, l , whereby it may be turned to elevate or depress the eccentrics. It will be seen that provision is thus made for readily discontinuing the pressure of the rollers a upon the fluted rollers.

To prevent removal of the pressure from the rollers a when the machine is running, I provide means whereby the movement of the rock-shaft which elevates the eccentrics and removes the pressure from the rollers a is prevented when the driving-belt is on the fast pulley, so that the pressure can only be removed when the driving-belt is on the loose pulley, thus preventing discontinuance of the pressure by carelessness or accident while the machine is in operation. To this end I provide the rock-shaft i with an arm, n , having a rod, o , which projects downwardly and bears at its lower end upon the shipper-bar p , when the latter is in the position it occupies when the driving-belt q is on the tight pulley r , and coincides with an orifice, t , in said shipper-bar when said bar is moved to the position it occupies when the belt is on the loose pulley s . The movement of the rock-shaft required to raise the weights c causes said rod to enter the orifice t ; but the shipper-bar prevents the rock-shaft from being so moved until the ship-

The shipper-bar may be operated by any suitable means, preferably by crank-rods *u*, journaled in suitable supports at convenient points along the frame, and having slotted crank-arms *v* engaging with studs *w* on the shipper-bar.

The rock-shaft with its eccentrics and the shipper-bar having the described connection with the rock-shaft constitute the best means 25 of which I am at present aware of carrying my invention into effect. I do not limit myself, however, to these devices, as others may be substituted for them without departing from the spirit of my invention.

30 My improvements are applicable not only to spinning-frames, but also to drawing-frames, mules, speeders, and other like machines.

I claim—

1. The combination of the rollers *a* and *b*, devices, substantially as described, whereby pressure is applied to the rollers *a*, with mechanism whereby said pressure may be removed, and devices, substantially as described, whereby the operation of the pressure-removing mechanism is prevented when the machine is running, and the starting of the machine is prevented while the pressure is removed, as set forth. 35 40

2. The combination of the rollers *a* and *b*, the weights *c*, and levers *d*, whereby pressure is applied to said rollers *a*, with the rock-shaft *i*, having eccentrics *k*, arm *n*, and rod *o*, and the shipper-bar *p*, having an orifice adapted to coincide with said rod only when the driving-belt is inoperative, whereby the removal of the pressure on the rollers *a* is prevented when the machine is running, and the starting of the machine is prevented when the pressure is removed, as set forth. 45 50

In testimony whereof I have signed my name to this specification, in the presence of two subscribing witnesses, this 2d day of November, 1883.

WILLIAM KELLEY.
